UNITED STATES PATENT OFFICE.

HARRY D. BARTLETT, OF CHICAGO, ILLINOIS.

FOLDABLE FURNITURE.

1,295,839.

Specification of Letters Patent.

Patented Mar. 4, 1919.

Application filed March 18, 1916. Serial No. 85,054.

To all whom it may concern:

Be it known that I, HARRY D. BARTLETT, a citizen of the United States of America, and a resident of Chicago, county of Cook, 5 and State of Illinois, have invented certain new and useful Improvements in Foldable Furniture, of which the following is a specification.

This invention relates to furniture which 10 may be readily collapsed, or folded for portability or storage and which may be easily set up ready for service; and more particularly to folding chair and table sets adapted for camp, club, motor-boat and 15 automobile use, and wherever compact portable units of such character may be desired.

Heretofore the need of providing or improvising suitable table and seating means for picnic and outing parties has usually 20 been difficult to meet satisfactorily, ordinary furniture being ill adapted for portability and improvised devices usually being deficient and inconvenient.

The main objects of this invention are to 25 provide an improved form of folding chair and table set; to provide an improved form of table adapted to fold in such manner as to furnish storage space; to provide a folding chair of improved form adapted either 30 to stand by itself or to be attached to a row-boat seat or the like; to provide a chair adapted when folded either to stand stably on edge or to serve as a hat rack when hung on the wall; and to provide a 35 portable table and chair outfit including a table and a plurality of chairs constructed for combining in a unitary set when folded adapted for outing purposes, as by automobile, motor-boat and the like.

40 Illustrative embodiments of this invention are shown in the accompanying drawings in which—

Figure 1 is a side elevation of a folding chair.

45 Fig. 2 is a horizontal section through the back on the line A—A of Fig. 1.

Fig. 3 is a front view of the chair.

Fig. 4 is a vertical section through the back on the line B—B of Fig. 3.

50 Fig. 5 is a fragmentary medial cross-section from back to front of a modified form of seat.

Fig. 6 is a fragmentary section on the line C—C of Fig. 3.

Fig. 7 is a section on the line D—D of 55 Fig. 1.

Fig. 8 is a section on the line E—E of Fig. 11.

Fig. 9 is a medial section from side to side on the line F—F of Fig. 5. 60

Fig. 10 is a side view of the chair of Fig. 1, in folded position.

Fig. 11 is a fragmentary outside view of a modified construction of the legs at the X-pivot. 65

Fig. 12 is a perspective view of the seat frame.

Fig. 13 shows the pivot bolt for the back.

Fig. 14 is a fragmentary section taken length-wise of a row-boat with the chair 70 of Fig. 1 installed therein.

Fig. 15 is an end view of a folding table with a set of four chairs folded therein.

Fig. 16 is a side view of the table and chairs shown in Fig. 15. 75

Fig. 17 is a perspective view of one of the leg fastening locks on the folded table.

Figs. 18 and 19 are enlarged fragmentary views of the leg brace fastening released from and clamped to the leg respectively. 80

Fig. 20 is an inverted perspective view of the table with the legs unfolded and the chairs removed.

In the construction shown, the combination furniture set comprises a folding table 85 1 and a plurality of folding chairs 2, the latter being inclosed and held in place by the table legs or supporting means 3, folded thereon in a compact and unitary manner.

Each chair 2 comprises a seat 4, a back 90 5, and supporting means all joined together in mutually turnable relation adjacent to the back edge of the seat. For this purpose a common pivot or bolt 6 passes through suitable parts or perforated lugs disposed 95 coaxially on said seat 4, back 5 and supporting means 3. The said supporting means comprises complementary members 7 and 8 joined together medially at the coaxial points 9. One of the leg means 7 100 105 is formed to receive the bolt 6, loops 10 being provided therefor, and the ends 11 being extended diagonally downward across the chair, in bracing position, and secured to the other side, as by the pivots 9. Where the ends 11 cross, they are fastened together as by a rivet 11.1. The complementary leg 8 at its upper end coacts detachably with

a fastening or lug 12 on the lower side of the seat adjacent to the front edge.

The seat 4 comprises a border frame 14 and a body part secured thereto in a unitary manner, said body part including a sheet metal plate 15 and a wooden panel 16 or the like, which may be upholstered if desired, secured thereto, as by screws 17. Said frame 14 consists of a bent rod of resilient character having its front part disposed across the front of the seat and having its side parts disposed rearwardly on opposite sides of the seat. The plate 15 has its edges turned downward and inward tightly against said rod in clamping relation thereto. The frame rod 14 is looped at the rear edge of the seat, forming a pair of lugs 20 adapted to receive the pivot 6. Said rod extends upward from each lug 20 and is looped backward somewhat at the top to form a bracket or arm 22 having a socket 23 adapted to receive and support a coacting part of the back 5. From the socket 23 the rod 14 extends downward and forward diagonally to a medial point on the side where it turns inward horizontally and terminates in a turn or loop 26 about an upward hump 27 in said rod. The socket 23 is formed to utilize the resilience of the rod 14 for yieldably engaging the side bars of the forwardly swingable back 5. In order to permit of readily attaching the seat 4 to the seat 28 of a canoe or row-boat or the like 29, or to permit of hanging the folded chair on a horizontal rail or cleat, as will be understood, a hook or lug 30 is provided on the underside of the seat. For this purpose, the frame rod 14 is looped downward and backward forming a broad rearwardly facing lug of resilient character adapted to grip whatever the seat is to be attached to.

The back 5 comprises a frame of inverted U-shape, consisting of a resilient rod 35 having its central part bowed backward medially to fit the back of the user, and having its ends turned downwardly and looped at the lower extremities to form lugs 37 adapted for receiving the pivot 9. Attached to the upper part of said frame is a body part 38, consisting of a plate of sheet metal having its top and side edges folded back around the frame rod in tightly clamped relation and imparting a unitary character to the back. When the back is folded forward, the body plate 38 swings down to a plane substantially parallel with and in front of the seat 4, and the side rods of the back are then disposed on opposite sides of the seat, the downward swing of the back being limited at 26 by the inwardly turned extremities of the rod 14, adjacent to the hump 27. When the back is swung to its normal position, the side rods are sprung into the sockets 23, and the back so held is comfortably yielding, the coacting parts 35

and 14 having sufficient spring to provide an amplitude of about two inches for the top of the back. The yielding is mainly in the bars 35 and in the ends of bar 14 near the hump 27.

The leg 7 is U-shaped and has the upper ends of its side arms pivoted to the seat, the cross member 41, at the opposite end, serving as a broad tread shoe or foot adapted to support the chair stably, even on soft ground.

The leg 8 is rectangular, one end 43 serving as a broad bearing foot like foot 41, and the other end 44 serving to engage the catch 12 when the chair is in use. The medial pivots 9 are disposed somewhat toward the upper ends of the legs from the center, so that when extended X-wise, a broad stable support is provided by said legs. When folded, the front foot 41 projects upward beyond the back, and serves as a handle for carrying the chair. When so folded, the other foot 43 extends back of the seat and pivot 6 and may also be used as a handle, and is especially adapted and positioned for hanging the chair on wall hooks in such manner as to render the back supports 22 well adapted to serve as hooks of a hat rack or the like, as will be understood.

The leg device or supporting means 3 is detachable as a whole from the back and seat proper, by removing the bolt 6, withdrawing said means 3 and then returning said bolt. The remaining back and seat members constitute a very simple and desirable form of seat, adapted for attaching to any of the numerous forms of backless seats commonly in use, such for instance as found on many wagons and on row boats and canoes. Being foldable, the back may be swung forward when the boat or other device is not in use, so as to avoid injury either in passing under a low object, or when for any reason it is desired to arrange the devices compactly.

When the invention is applied to a row boat, the legs may to advantage be merely swung back of the seat and used as a frame on which to place any extra clothing well up away from such moisture as may collect in the bottom of the boat, as for instance when one is fishing. As thus used, the leg member 7 is disposed horizontally or nearly so, and leg 8 stands foot end up with the other end 44 resting on the bottom of the boat. The upper or forward part of leg means 7, having the crossed bars 11, serves as a convenient shelf on which the tackle box 45 and the like may be kept safely and conveniently at hand and out of one's way.

The yielding back makes the chair very comfortable, for whatever purpose it is used. This feature is of especial advantage when the chair is utilized as an extra seat in an

automobile or other vehicle subject to jolts and sudden changes in speed and direction.

When said supporting means 3 is attached to the seat, the chair as such operates as follows: In folding the device, the back having been swung forward, the feet members are first drawn together, thereby releasing the upper end 44 of member 8 from the seat catch 12. The foot 41 and end 44 are then swung together and the leg members thereby folded to a common plane. Then the leg members are swung as a unit against the bottom of the seat. The device is then secured in its folded condition by 15 swinging the latch 46 on the leg member 7 down over the upper edge of the folded back 5.

When folded, the chair may be set on end on the floor where it will stand stably, resting on the foot 43 of leg 8 and braced by the brackets 22, which in the folded position are adjacent to said foot (see Fig. 10).

If a horizontal wall cleat is convenient, the chair may be hung thereon in its folded condition by means of the lug 30, as will be understood. If wall hooks are more convenient, and if desired, the chair may be hung thereon, pivot edge up, by means of the foot member 43 so that the two braces 22 25 may serve as hooks, as above explained.

To unfold the chair the catch 46 is released, the legs are together swung back away from the seat, then the end 44 is swung upward away from foot 41 and is 35 forced under the catch 12. The back 5 is then swung up into place and the side bars 35 snapped into engagement with the sockets 23.

In order to retain the full strength of the 40 light leg bars at the point of pivoting together at 9, the apertures for the pivots may be swaged rather than drilled, or reinforcing channels 51 may be provided as shown in Figs. 8 and 11.

45 In the simplified embodiment of Figs. 5 and 9, the plate 15', which may be a sheet metal stamping, is used alone without any wooden panel or upholstering. Said plate may be pressed or otherwise formed to correspond in shape with the usual chair seat. The rear part of the seat is reinforced by turning up the edge at 15".

The table 1 comprises a top or body member 60, which may be of usual construction, 55 preferably rectangular and oblong, and a pair of supporting means or leg members 3, attached to opposite ends thereof.

Each of said leg members comprises a rectangular frame jointed medially at points 60 63, located a short distance from the underside of the table. The upper or short end 65 of each leg member is secured rigidly to the table, as by screws 66. The complementary lower swinging part 67 constitutes a wide 65 bearing member with a long cross foot 68,

adapted to rest stably wherever the table may be used, either indoors or outside, and regardless of the character of the ground, said foot presenting a large, flat surface adapted to prevent the leg from sinking in 70 case the ground or turf is soft and yielding.

Fastenings are provided to secure the legs in their upright position. For this purpose, U-shaped rods 70 are attached pivotally to the underside of the table, by means of bearing clamps 72 embracing the cross-member 73 of said bars, adjacent to the opposite sides or arms 75. The free ends of said arms are adapted for clamping to the leg members adjacent to the feet, said legs being provided 75 with notches 77 and said braces having loops 78 on their ends on which are carried bolts 79, with suitable thumb nuts 80, adapted for ready setting by hand when the legs are extended. The short inner ends 65 of the legs 85 are made of precisely sufficient length to permit of folding the swinging ends 75 inward, parallel to and overlapping each other when the chairs are in place.

In order to secure the table legs in their 90 folded position with the chairs embraced thereby, locking means are provided consisting of a pair of bolts or bars 83 disposed longitudinally on the inner side of the foot member 68 of the outermost support, said 95 bolts being slotted lengthwise at 85, and slideable on the fixed guide studs 86 for sliding outward to engage the opposite leg member, as shown in Figs. 17 and 20.

The leg and foot members are formed of 100 angle bars reinforced at the lower end by suitable gusset plates 88. One of the leg members having the locking bolts on the foot is somewhat broader than the opposite leg member and is notched at 89 on the 105 inner side at the ends of the foot so as to permit the leg members to nest together snugly when folded. The locking bolts are so disposed as to overlie the part 67 of the opposite leg when the device is folded, as 110 shown in Fig. 17.

The table may be designed to hold either more or less than four chairs if preferred, but four is a number which meets the usual requirements. In packing the chairs in the 115 table, they are in any case preferably arranged in groups of two placed seat to seat and arranged so that the brackets 22 of the outer chair will bear against the inner side of the peripheral flange 91 on the under side 120 of the table, said flange preferably having definite notches or pockets 92, therein, to receive said brackets so as to prevent any edge-wise movement of the chairs.

On the opposite side of the table from said 125 notches an upstanding lug or plate 95 is provided for each pair of chairs, adapted to engage or enter the foot member 43 of the inner chair. For this purpose angle bars are screwed to the underside of the table. The 130

opposite foot 41 bears against the adjacent table flange 91. When the table is designed for more than one pair of chairs, as for instance four chairs, the pockets 92 and flanges 95 are preferably arranged oppositely for the different groups, as shown in Fig. 20. When the folded chairs are assembled in pairs and the table legs 3 are folded and locked thereon, the several parts or members 10 are held together in a very compact and rigid manner, forming a unitary furniture outfit. In case it is desired to omit one pair of chairs, and so leave a blank chair space in any instance, the chairs inclosed are prevented from sliding sidewise by the sockets 92 and the coacting lug 95.

When the folded chairs 2 are in place and the table legs have been folded thereon and locked in place by the bolts 83, the chair and 20 table set as a whole is preferably placed in a canvas bag or protective casing (not shown), whereupon the outfit may be placed in or strapped to an automobile, or otherwise transported or stored as may be desired.

25 Although but one embodiment of the table member and only two embodiments of the chair members are herein set forth, it is to be understood that numerous details of the constructions shown may be altered or omitted 30 without departing from the spirit of this invention as defined by the following claims.

I claim:

35 1. A seat, comprising a unitary border member, in combination with a body member, said border member consisting of a bent rod having its front part disposed across the front of the seat and having its side parts disposed rearwardly on opposite sides of the seat, and provided with loops at the 40 rear edge of the seat, said side parts being formed each with an upward extension including a rearward loop and with the extremity of the rod extending diagonally forward and downward and secured to the 45 side part between the front and back edges of the seat, and a back turnably connected to the first mentioned loops and normally engaged by the rearward loops to limit its backward swing.

50 2. A foldable chair comprising a seat having a pair of rearwardly inclined upstanding lugs at its rear corners adapted to serve either as stops or as feet, a back swingable back against said lugs to its seating position

55 tion and leg means foldable against said seat and projecting backward therefrom when folded to substantially the same extent that said lugs project backward, whereby the seat will stand stably on said lugs and leg means when the chair is folded.

60 3. In a chair, a supporting member of unitary character, comprising a bar bent to include a horizontal foot extending crosswise from one side of the chair to the other, said bar being turned up at the ends of 65 said foot, the upturned parts extending upward and each including a looped part and said bar extending diagonally downward and inward from the looped parts and having its ends attached to the middle parts of 70 the opposite upturned parts respectively.

4. In a chair, a seat having pivot means adjacent to its rear edge, a supporting member of unitary character comprising a bar bent to include a horizontal foot extending 75 crosswise from one side of the chair to the other, said bar being turned up at the ends of said foot, the upturned parts extending upward and each including a looped part formed to receive said pivot means and said bar extending diagonally downward and inward from the looped parts and having its ends attached to the middle parts of the opposite upturned parts respectively, and a complementary supporting member turnably connected medially to the first mentioned supporting member and having a foot at one end and its opposite end being adapted to detachably engage the front part of 80 said seat.

5. A chair, comprising a seat in combination with a back, supporting means each turnably connected coaxially to the back part of said seat, lugs projecting upward on the back part of said seat adapted to limit 95 the rearward swing of the back in unfolding the chair, said supporting means being foldable against the seat member and projecting beyond the rear edge of the seat, said lugs each being substantially rigid 100 against inward springing and including a diagonal brace part, whereby the lugs are better adapted to effectually hold the chairs in place when folded and stored in a suitable container.

Signed at Chicago this 15th day of March, 1916.

HARRY D. BARTLETT.
